UNITED STATES PATENT OFFICE.

JOHN WILLIAM HUNZE, OF CAPE GIRARDEAU, MISSOURI.

SEEDER ATTACHMENT.

No. 895,022.

Specification of Letters Patent.

Patented Aug. 4, 1908.

Application filed March 9, 1908. Serial No. 420,035.

To all whom it may concern:

Be it known that I, JOHN WILLIAM HUNZE, a citizen of the United States, residing at Cape Girardeau, in the county of Cape Girardeau and State of Missouri, have invented certain new and useful Improvements in Seeder Attachments; and I do declare the following to be a full, clear, and exact description of the invention, such as will enable others skilled in the art to which it appertains to make and use the same.

My invention relates to seeder attachments, and especially to devices which are adapted to mark the point of dropping of the seed, so that equal rows may be formed entirely across the field to be planted.

Heretofore in numerous seeders it has been necessary to stretch a wire entirely across the field, and operate the seeder mechanism by knots or projections carried upon the wire.

The mark mechanism here only consists of lugs or projections carried by the wheels, and frequently in turning it was difficult to get the seeder mechanism started properly, and 25 to get the marks properly alined so that the rows would be even and symmetrical.

It is the object of my invention to obviate these difficulties and provide a device of this character which may be attached to an ordinary seeder so that it will finally discharge the seed at given points and simultaneously therewith mark the point of discharge.

A further object of the invention is the provision of means whereby the marker may be rendered inoperative upon turning curves or in going from one point to another which it is not desired to plant, and simultaneously throwing out of action the seeder mechanism. I also provide means for keeping the marker 35 of one wheel in alinement with the other, and means for adjusting the several parts to fit different sized wheels and different sized frames.

Further objects of the invention will appear as the specific description which follows is read in connection with the accompanying drawings, in which

Figure 1 is a top plan view of the device, Fig. 2 is a section on the line 2—2 of Fig. 1, 50 and Fig. 3 is a section on the line 3—3 of Fig. 1.

Referring more especially to the drawings, 1 represents the frame, which is composed of side bars 2, end members 3, a longitudinal central member 4 and an intermediate transverse member 5, which is secured to the side members 2 and the longitudinal member 4 by

any suitable means. Journalled in bearings in the side members 2 and in the rear end of the intermediate member 4 is the main supporting axle or shaft 6, upon which the usual supporting wheels 7 and 8 are carried. These wheels are keyed properly to the shaft, and the shaft revolves in the bearings within the frame. Loosely mounted upon the shaft adjacent the side frame is a collar 9, which is 60 provided with an annular groove 10 intermediate its length and adjacent its inner end is a gear wheel 11. A similar collar 12 with an annular groove 13 and a gear 14 is secured upon the opposite side of the shaft, and is provided 65 with an extension arm 15, to which is secured an eye bolt 16 to be hereinafter described.

Keyed to the shaft adjacent the collar 12 is a small ring 17, which is adapted to hold the shoe supporting band 18 in proper position upon the axle. This shoe supporting band 18 is provided with a pair of lugs projected from its periphery, the outer one of which, 19, is adapted to receive a spiral spring 20, which connects with the lug 21, 70 carried upon the upper arm 22 of the marker shoe 23. The upper arm 22 is adjustably mounted upon the lower arm 24, and is held in adjusted position by a set screw 25. The lower arm is pivoted to the inner lug 26, and 75 is connected by a link 27, secured to the eye bolt 16 upon the collar 12. Upon the opposite side of the frame the collar 9 is provided with an annular groove 28, in which is secured a collar 29, formed in two halves and 80 held together by set screws 30. Each part is provided with an operating paddle 31, which engages the rocker arm 32 rotatably mounted upon a stub shaft 33, carried by one of the side members 2 of the frame. The 85 end of this rocker arm is connected to a link 34, provided with a central turn buckle 35, to adjust its length so that it may be regulated for different lengths of frames or machines. The opposite end of the link is 90 pivotally secured to the counter shaft 35', which controls the mechanism in the seed boxes 36. Each collar 9 and 12 is provided with a pair of axially alined parallel arms 95 37, which engage diametrically opposite 100 grooves 38, formed upon the band 18.

Secured to the rear end of the intermediate member 4 so as to overhang the axle 6 is a bearing member 39 having a socket 40, in which is journalled the shaft 41, upon which 110 the crank arms 42 and the foot lever 43 is secured. To each one of these arms 42 I

secure a link 43' divided into two parts connected by a turn buckle 44. The inner part of the link 43' of that part adjacent the arms is provided with an offset 45, which is adapted to take over the shaft when the foot lever is in its lowermost position, so as to lock the collars 9 and 12 in their retracted position as will be hereinafter described. The opposite ends of the links are passed through 10 bearings in the side members of the frame and are attached to a pair of oppositely curved arms 46, which engage the annular recesses 10 and 13 of the collars 9 and 12.

In operation the spiral springs hold the 15 shoes 23 in engagement with the periphery of the wheel and in such forcible engagement with the band 18 that the collars 9 and 12 travel around the axle and the collar 9 carries the seeder operating paddles so as to 20 operate the rocker arm 32, and feed the seed from the seed boxes 36. When the end of the row is reached and the operator wishes to turn the machine around he presses down upon the foot lever 43 and thus retracts the 25 collars 9 and 12 from their normal position. This action through the links 27 withdraws the shoes 23 from the wheels against the action of the spring 20, and at the same time throws the paddles 31 out of the path of the 30 rocker arm 32. By pressing the foot lever all the way down the alignment of the links 43 pass the center of the shaft 41, owing to the engagement of the offset portion 45 with the shaft thereby locking the collars in such 35 position until the operator inserts his foot beneath the lever 43, and releases it. The spring pressure upon the shoes is sufficient to return the parts to normal and clamp the shoes against the wheel. In order to 40 keep both shoes in alignment I extend across the frame a transverse shaft 47 with an elongated gear 48 on each end so as to mesh with the gears 11 and 14 in all positions of their longitudinal movement upon the shaft 6.

45 From the foregoing description, taken in connection with the accompanying drawings, the construction and operation of the invention will be readily understood without requiring a more extended explanation.

50 Various changes in the form, proportion and the minor details of construction may be resorted to without departing from the principle or sacrificing any of the advantages of this invention as defined in the appended claims.

Having thus described my invention what I claim and desire to secure by Letters-Patent is:

1. In a device of the class described, the

combination with a frame, a supporting 60 axle running therethrough, traction wheels mounted thereon, markers carried by said axle, resilient means to hold said markers in engagement with the periphery of the wheels whereby they will rotate therewith, means 65 for disengaging the markers and means to adjust the markers for different sized wheels.

2. In a device of the class described, the combination with a frame, of a supporting axle therefor, traction wheels upon said axle, 70 markers carried loosely by said axle, a spring to hold said markers in engagement with the periphery of the wheels whereby they will be rotated with the wheels, means under control of the operator for releasing the markers 75 from connection with the wheel, means for holding the markers in alignment and means to adjust the markers for different sized wheels.

3. In a device of the class described the combination with a frame, of a supporting 80 axle therefor, traction wheels thereon, a pair of collars surrounding the shaft on either side of the frame, one of each pair being slidably mounted upon the shaft and both being loosely mounted thereon, a pair of marker 85 arms carried adjacent the traction wheels upon the collars, resilient means for holding the markers in engagement with the periphery of the wheel, means engaging the slidably mounted collars for operating the same, a 90 link connection between the collars and the markers, a reciprocal connection between the two collars, a connection between the reciprocal collars on either side of the frame for keeping the markers in alignment and means to 95 adjust the markers for different sized wheels.

4. In a device of the class described, a traction wheel, a marker, a spring for holding the marker in engagement with the traction wheel whereby it will be rotated thereby and 100 means to adjust the markers for different sized wheels.

5. A marker for seeder planters comprising an arm composed of separable adjustable sections one of which is pivotally carried by the axle, a shoe carried by the other section for frictional engagement with the periphery of the wheel so that the arms may be rotated thereby and a spring for holding the shoe in engagement with the wheel.

In testimony whereof I have hereunto set my hand in presence of two subscribing witnesses.

JOHN WILLIAM HUNZE.
